CLAIM

The ornamental design for a corner protector, as shown and described.

DESCRIPTION

FIG. 1 is a top plan view showing my new design;
FIG. 2 is a front elevational view thereof;
FIG. 3 is a rear elevational view thereof;
FIG. 4 is a bottom plan view of my new design;
FIG. 5 is a right side elevational view of my new design, the right side and left side views being mirror images and symmetrical; and,
FIG. 6 is a top front right perspective view of my invention.
